UNITED STATES PATENT OFFICE.

ALFRED H. F. STRAUB, OF LOS ANGELES, CALIFORNIA.

STEAM-ENGINE.

SPECIFICATION forming part of Letters Patent No. 404,573, dated June 4, 1889.

Application filed July 30, 1888. Serial No. 281,359. (No model.)

To all whom it may concern:

Be it known that I, ALFRED H. F. STRAUB, of Los Angeles, in the county of Los Angeles and State of California, have invented a new 5 and Improved Steam-Engine, of which the following is a full, clear, and exact description.

The object of the invention is to provide a new and improved steam-engine which is simple and durable in construction and very 10 effective in operation, avoiding all dead-points by transmitting the power directly to the main driving-shaft.

The invention consists of certain parts and details and combinations of the same, as will 15 be fully described hereinafter, and then pointed out in the claims.

Reference is to be had to the accompanying drawings, forming a part of this specification, in which similar letters of reference indicate 20 corresponding parts in all the figures.

Figure 1 is an end elevation of the improvement. Fig. 2 is a plan view of the same. Fig. 3 is an enlarged transverse section of the same on the line $x-x$ of Fig. 2. Fig. 4 is an 25 enlarged sectional side elevation of part of the improvement on the line $y-y$ of Fig. 3. Fig. 5 is a side elevation of part of the valve-gear. Fig. 6 is an enlarged sectional plan view of the steam-inlet on the line $z-z$ of Fig. 30 1, and Fig 7 is a detail end elevation of one of the pawls.

The improved steam-engine is provided with two cylinders A and A', placed in the same horizontal plane alongside of each other and 35 mounted on a suitable frame W. In the cylinders A and A' are held to travel the pistons B and B', respectively connected with the piston-rods C and C', respectively extending through both ends of the cylinders A and 40 A'. The outer ends of the piston-rods C and C' are connected by transverse beams D and D', respectively, in the middle of which is secured a longitudinal bar E, mounted to slide in suitable bearings A² A³, formed on the inner side of the steam-cylinders A and A'. In 45 the middle of the longitudinal bar E and on its under side are formed the rack-teeth E', meshing into a gear-wheel F, mounted to rotate loosely on the main driving-shaft G, rotating in suitable bearings formed on the 50 frame W directly under the cylinders A and A'. On one outer end of the main driving-

shaft G is secured a large pulley G' for transmitting the motion of the engine to the machinery to be driven.

On the gear-wheel F are pivoted a number of double pawls H, arranged in a circle and each provided with two wings H' and H², standing at right angles to each other, and of which the wing H' of each double pawl H is 55 adapted to engage a ratchet-wheel I, secured by suitable means to the main driving-shaft G. The other wing H² of each double pawl H is adapted to engage a ratchet-wheel J', formed on the hub of a bevel gear-wheel J, 60 mounted to rotate loosely on the main driving-shaft G. When the wings H' of the double pawl H engage the ratchet-wheel I, the other wings H² are disengaged from the ratchet-wheel J', and vice versa.

The bevel gear-wheel J meshes into a bevel gear-wheel K, secured to a vertical shaft K', mounted to rotate in suitable bearings formed on the main frame W. The bevel gear-wheel K meshes into a bevel gear-wheel L, secured 75 on one end of the main driving-shaft G. Thus when the gear-wheel F is rotated in one direction and the wings H' of the double pawls H engage the ratchet-wheel I, then the main driving-shaft G is turned in the same direction 80 in which the gear-wheel F revolves. When the latter revolves in an opposite direction, the wings H² of the double pawls H engage the ratchet-wheel J', while the other wings H' glide over the teeth of the ratchet-wheel I. The bevel gear-wheel J, carrying the said ratchet-wheel J', is thus turned in the direction of the motion of the gear-wheel F, and the motion of the bevel gear-wheel J is transmitted by the bevel gear-wheel K to 85 the bevel gear-wheel L, which then travels in the opposite direction of the bevel gear-wheel J, thus imparting a rotary motion to the main driving-shaft G in the same direction as it had originally when the ratchet-wheel I was 90 rotated, as above described, so that a continuous rotary motion is imparted to the main driving-shaft G in whatever direction the gear-wheel F may be traveling.

On the bevel gear-wheel L is formed a pulley L', connected by a belt L² with a pulley L³, connected with the governor N for imparting the usual motion to the same. The governor N may be of any approved construc-

tion and adapted to open and close the valve N', connected with the steam-inlet pipe N². The valve N' also connects with the cut-off valve O, adapted to connect alternately with 5 the ports a and b, leading to the pipes P and P', respectively connected with the steam-chests Q and Q', respectively located on top between the cylinders A and A'.

In the steam-chests Q and Q' travel the 10 slide-valves R and R', respectively operating over the inlet-ports c and c', respectively leading to the ends of the cylinders A and A'. The slide-valves R and R' connect alternately 15 the ports c and c' with the exhaust-ports d and d', leading to the outside in the usual manner. The slide-valves R and R' are connected with each other by a rod R², and are placed in such a relative position that when 20 the slide-valve R connects its inlet-port c with its exhaust-port d the other slide-valve R' closes the exhaust-port d' and permits live steam to enter the inlet-port c'. When the 25 positions of the valves R and R' are changed, the relative positions of the valves to the ports are changed in a reverse manner to that above described.

In the middle of the valve-rod R² is secured a collar R³, pivotally connected with a lever S, mounted to turn on a stud S', secured to 30 the cylinder A', as is plainly shown in Fig. 3. On the lower end of the lever S is held a friction-roller S², traveling on top of a guide-bar E², secured to the longitudinal bar E, before mentioned. The ends of the guide-bar E² are 35 curved, and when the friction-wheel S² engages the left end of the said guide-bar it comes in contact with a friction-wheel E³, for changing the position of the lever S. The friction-wheel S², at the right-hand end of the 40 guide-bar E², comes in contact with the friction-roller E⁴, for again reversing the position of the lever S. The reversing of the lever S takes place suddenly when the pistons B and B' in the cylinders A and A' near the 45 ends of their strokes, so that the positions of the slide-valves R and R' in the steam-chests Q and Q' are changed after the inlet and exhaust of steam from the ends of the cylinders A and A'.

50 In order to use the steam expansively, I provide the cut-off valve O, before mentioned, which is connected with a valve-stem T, having a wing T' extending into a slot formed in the said valve O, as is plainly shown in Fig. 55 6. Thus when the valve-stem T is turned the wing T' turns the said valve and opens or closes the ports a and b, respectively. On the lower end of the valve-stem T is secured a forked arm, U, provided on its forked ends 60 with friction-rollers U' and U², traveling in guideways E⁵ and E⁶, formed on one side of the guide-bar E², as is plainly shown in Fig. 5. Thus when the pistons B and B' in the cylinders A and A' make two-thirds of their 65 strokes the valve-stem T is turned by the action of the guideways E⁵ and E⁶ on the friction-rollers U' and U² on the said valve-stem,

whereby the valve O cuts off sooner or later the ports a and b, thus preventing an entrance of steam to the respective steam-chests Q or Q'. 70

The operation is as follows: The two pistons in the cylinders A and A' are located directly opposite each other to travel together forward or backward in the said cylinders A and A' whenever steam is admitted 75 through the respective ports c and c' in the respective ends of the cylinders a and a'. The forward and backward motion of the pistons in the cylinders a and a' causes a forward and backward sliding motion of the longitudinal bar E, which, by its rack-teeth E', imparts a rotary motion forward and backward to the gear-wheel F. The rotary forward and backward motion of the latter is converted into a continuous rotary motion 80 imparted to the main driving-shaft G by the means above mentioned—that is, the double pawls H, the ratchet-wheel I, secured on the main driving-shaft G, and the bevel gear-wheels J, K, and L. As the positions of the 85 slide-valves R and R' in the steam-chests Q and Q' are not changed until the pistons near the ends of their strokes, the exhaust-steam in front of the piston can freely escape. The guideways E⁵ and E⁶ are so arranged that the 90 valve O cuts off the live steam when the pistons have made about two-thirds of their strokes.

Having thus described my invention, what I claim as new, and desire to secure by Letters 100 Patent, is—

1. In a steam-engine, the combination, with cylinders and pistons operating in the same, of steam-chests held on the said cylinders, slide-valves held in the said steam-chests, a 105 valve-rod connecting the said slide-valves, a lever pivotally connected with the said valve-rod, and a bar secured to the pistons and sliding between the cylinders and operating on the said lever to shift the said slide-valves, 110 substantially as shown and described.

2. In a steam-engine, the combination, with cylinders and pistons operating in the same, of steam-chests held on the said cylinders, slide-valves held in the said steam-chests, a 115 valve-rod connecting the said slide-valves, a lever pivotally connected with the said valve-rod, a bar having a reciprocating motion derived from the said pistons and operating on the said lever to shift the said slide-valves, 120 and a cut-off valve connected with the said steam-chest and controlled by the said bar, substantially as shown and described.

3. In a steam-engine, the combination, with a cut-off valve, of a valve-stem carrying the 125 said valve, a forked arm held on the said valve-stem and provided with friction-rollers, and a bar having a reciprocating motion derived from the action of the pistons, the said bar being provided with guideways for the 130 said friction-rollers, substantially as shown and described.

4. In a steam-engine, the combination, with two slide-valves and a valve-rod connecting

the said slide-valves, of a lever pivotally connected at one end with the said valve-rod and provided at its other end with a friction-roller, a bar having a reciprocating motion derived from the pistons, guideways formed on the top of the said bar and on which travels the said friction-roller, and stop-

wheels held on the top of the said bar for reversing the said lever, substantially as shown and described.
